UNITED STATES PATENT OFFICE.

WILLIAM A. GALBRAITH, OF FLINT, MICHIGAN.

CARRIAGE-POLE.

SPECIFICATION forming part of Letters Patent No. 224,171, dated February 3, 1880.

Application filed December 1, 1879.

To all whom it may concern:

Be it known that I, WILLIAM A. GALBRAITH, of Flint, in the county of Genesee and State of Michigan, have invented a new 5 and useful Improvement in Carriage-Poles, of which the following is a specification.

Figure 1 is a plan view of the under side of the pole. Fig. 2 is a side view. Fig. 3 is a transverse sectional elevation on line *x x*, 10 Figs. 1 and 2.

Similar letters of reference indicate corresponding parts.

This invention relates to that class of carriage-poles that are capable of being adjusted 15 and readily fitted to vehicles of any width; and the object of the invention is to decrease the weight of the poles and make them more durable and effective in their operations.

The invention consists of the combination 20 of a slotted ratchet-faced plate secured to the under side of the carriage-pole, of circle-bars hinged to the rear end of the pole, of adjustable side stays or braces connected by a cross-bar that moves between the pole and the slotted plate, and of hinged pole eyes or sockets in the ends of the side braces.

In the drawings, *A* represents a carriage-pole, having secured to its under side by bolts, rivets, or otherwise a longitudinally-slotted 25 plate, *B*, whose face is ratcheted, as shown at *a*. A cross-bar, *C*, is set laterally between the pole *A* and plate *B*, and is held by the screw-bolt *b*, while between the nut *f* of said bolt *b* and the ratcheted face of the plate *B* is a washer, *c*, which is provided with teeth that engage 30 in the depressions of the ratchet-face of the plate *B*. This cross-bar *C* connects the forward ends of two curved side stays or braces, *D*, which spread apart and extend rearward 35 to connect with the thill-clips of the vehicle.

On the rear end of the pole *A* is a box or socket, *E*, in which are hinged two circle-bars, *F F*, that curve laterally and connect by bolts, rivets, welding, or otherwise with the braces 40 *D* near their free ends, and operate as laterally-adjustable supports to the said braces or stays *D*.

G represents a pivoted pole eye or socket

to fit in the thill-clips, and *H* is a downwardly-projecting pin that is designed to enter the 50 cross-bar, to which the whiffle-tree of the vehicle is pivoted. The side stays or braces, *D D*, have sufficient elasticity to permit of their expansion and contraction, or their opening and closing, within certain limits, so that the device may be adapted to vehicles of different 55 widths.

If the cross-bar *C* be pushed forward in the direction of the arrow, Fig. 1, the pole-eye ends of the side braces, *D*, are brought nearer 60 together, so that the device can be applied to a narrow vehicle, while if the cross-bar *C* be moved in the reverse direction the ends of the braces *D* are pushed apart to accommodate the device to a wider vehicle.

The cross-bar *C* and braces *D* are in all cases firmly held in position by the bolt, nut, and washer *b f c*, or other convenient devices, that operate to hold the said bar to the plate *B*.

The hinging of the circle-bars *F F* in the 70 socket *E* gives them the required range of adjustability, that they may adapt themselves to the movements of the side braces, *D*.

The pivoted pole eye or socket *G* increases 75 the adjustability of the pole.

Having thus described my invention, I claim as new and desire to secure by Letters Patent—

1. In combination with the pole *A*, the slotted and ratcheted plate *B*, cross-bar *C*, side 80 stays or braces, *D D*; and fastening device *b c f*, constructed and arranged substantially as and for the purpose described.

2. In combination with the pole *A*, the slotted and ratcheted plate *B*, cross-bar *C*, braces 85 *D D*, socket *E*, and hinged circle-bars *F F*, substantially as herein shown and described.

3. The combination, with the pole *A* and cross-bar *C*, of the notched plate *B*, toothed washer *c*, screw-bolt *b*, and nut *f*, as and for 90 the purpose specified.

WILLIAM A. GALBRAITH.
